DESIGN FOR A DOLL

Aune S. Hill, Verdi, Nev.

Application November 27, 1944, Serial No. 116,561

Term of patent 14 years

(Cl. D34—4)

To all whom it may concern:

Be it known that I, Aune S. Hill, a citizen of the United States, residing at Verdi, in the county of Washoe and State of Nevada, have invented a new, original, and ornamental Design for a Doll, of which the following is a specification, reference being had to the accompanying drawings, forming part thereof.

I claim:

The ornamental design for a doll, as shown.

AUNE S. HILL.
